JAR

Shannon A. Erwin, Brea, Calif., assignor, by
mesne assignments, to Scientific Engineering
Company, a corporation of California

Application January 6, 1934, Serial No. 705,560

5 Claims. (Cl. 255—27)

This invention relates to oil well tools, and particularly to what are known as jars, used in connection with the operation of recovering stuck drills. In such cases the drill is engaged with a fish or spear and a jar is connected thereto in such a manner as to enable a sudden shock or jar to be imparted to the stuck tool, which aids in breaking the same loose.

The principal object of my invention is to provide a tool of this character in which the jarring action is had by the sudden and automatic release of liquid pressure in the tool, such release being occasioned by the resistance to dislodgement of the stuck drill. Such pressure and the means to utilize the same therefore form the essential features of this invention, and since the amount of pressure on the remote tool can be easily varied and as easily gauged at the surface, the operator may have accurate knowledge of operating conditions within the tool.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side view mainly in section of my improved jar showing the parts positioned at the start, or when the hydraulic pressure is initially applied.

Figure 2 is a similar view showing the impact unit under pressure and in the position occupied when it has slipped upwardly somewhat by the upward pull on the tool when engaged with a stuck drill.

Figure 3 is a similar view showing the position of the impact unit after the liquid pressure has been released and the jarring impact has been made.

Referring now more particularly to the characters of reference on the drawing, the body of the tool is of hollow cylindrical form and for convenience of assembly comprises upper and lower sections 1 and 2, removably but rigidly connected together at their adjacent ends. Slidably but non-turnably mounted in a bearing 3 formed at the upper end of the section 1 is the spindle 4 of the impact unit which at its upper end above the body is connected to a coupling head 5 which is preferably the same diameter as the body. This head in turn is connected to the adjacent sec-

tion 6 of the string of conventional drill pipe. This pipe extends to the top of the well as usual, and is there connected as is customary to the torque bar or Kelly bar as it is commonly called, and to which connection is made with a suitable source of water pressure.

The string of pipe communicates with a vertical passage 9 which extends through the head 5 as well as through the spindle 4 to the lower end of the same. The spindle intermediate its ends carries an enlarged flange 10 which has a running fit in the main bore 11 of the upper body section 1, and which of course is relatively large compared to the diameter of the spindle and its bearing 3. A shoulder 12 is therefore formed in the body at the base of said bearing. The flange is positioned on the spindle so that when the head 5 and the body section 1 are in contact as shown in Figure 1, the flange is some distance below said shoulder, the latter of course limiting the upward movement of the spindle from such position.

Disposed about the spindle and extending downwardly from immediately under the flange 10 is an expandible tube 13 preferably of thick rubber so that it may withstand considerable pressure, the end portions only of said tube closely engaging the spindle as shown in Figure 2. Ports 9a are cut at intervals through the spindle to communicate with the passage 9 so that the liquid flowing therethrough may be directed against the inner surface of the tube.

The tube is closely surrounded by a sleeve 14 of resilient metal normally having a running fit in the body. Said sleeve is split longitudinally at various circumferentially spaced points as shown at 15 to enable said sleeve to deflect outwardly by an internal pressure in the tube. The tube and sleeve are held against longitudinal movement by and between the flange 10 and a flange-like nut 16 on the lower end of the spindle.

The lower end of the body section 2 is closed and projecting upwardly from the bottom of the same into the main hollow area thereof is a rigid pipe 17. This pipe terminates below the bottom of the spindle and is formed on its upper end with a seat for a ball valve 18. The pipe is freely open to the bottom of the section 2 which is provided with the usual tapering threaded portion 19 for connection to the shank or head 20 of any standard form of spear or fish, said shank having the customary vertical passage therethrough so that free communication with the adjacent end of the pipe is had.

Secured on and depending into the section 2

from the lower end of the spindle is a sleeve 21, surrounding the pipe and ball in spaced relation. At its lower end this sleeve is provided with a packing ring 22 slidably engaging the pipe with a liquid-tight fit. Projecting inwardly from the sleeve 21 are radially disposed pins 23. These pins are positioned so that when the head 5 is engaged with the body 1, they are some distance below the seated ball as shown in Figure 1. The transverse distance between the inner ends of the pins is greater than the diameter of the pipe so as to clear the same, but is less than the diameter of the ball. Therefore when the sleeve is raised the necessary distance the pins engage and raise the ball off its seat as shown in Figure 3.

In operation the jar with the spear attached thereto is lowered to engage the stuck tool, and after this is effected the head 5 is then disposed in its lowermost position relative to the body of the jar. Hydraulic pressure is then supplied to the vertical passage 9 and since the only outlet for the liquid (the pipe 16) is closed by the ball, the pressure will accumulate and expand the tube 13. This causes the metal sleeve to similarly expand and grip the internal wall of the body. This pressure is sufficiently great to resist considerable upward pull, but since the grip is frictional only it will sooner or later yield due to the excessive resistance offered by a tightly stuck drill, and the impact unit will thus begin to slip upwardly in the body as the pull is continued. After a certain amount of such slip has taken place the pins 23 engage the ball 18 raising the same from its seat. The confined liquid is then suddenly released, since it is free to flow down into the well through the pipe 16. As a result the impact unit rises suddenly to its topmost position, the flange 10 engaging the shoulder 12 with a heavy impact or jar.

Since the body of the tool is connected to the spear, this jar is transmitted to the same and to the stuck tool engaged thereby with the desired loosening action. If one such operation is insufficient to effect this result, the spindle is again lowered so as to reseat the ball, the hydraulic pressure is reapplied to expand the tube and another jarring action is then effected. Such operations may be carried out as many times as necessary and in rapid sequence, since each recharging with the liquid consumes but little of the same and there is a very small space to fill before the pressure is effective.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A jar comprising a body adapted at its lower end for connection to a spear or like tool, a spindle slidable in and projecting from the upper end of the body for connection to a suspending means, means between the spindle and body positively limiting the upward movement of the spindle from a predetermined lowered position in the body, an expansible member mounted on the spindle within the body adapted when expanded to frictionally grip the inner wall of the body, hydraulic pressure means to thus expand said

member, and means within the body and functioning automatically after the spindle has moved upwardly a predetermined distance from said lowered position to suddenly relieve the hydraulic pressure.

2. A jar comprising a body adapted at its lower end for connection to a spear or like tool, a spindle slidable in and projecting from the upper end of the body for connection to a suspending means, means between the spindle and body positively limiting the upward movement of the spindle from a predetermined lowered position in the body, an expansible member mounted on the spindle within the body adapted when expanded to frictionally grip the inner wall of the body, hydraulic pressure means to thus expand said member, a liquid chamber in the body in free communication with the interior of the member whereby said chamber will fill with the liquid supplied to the member, an outlet from said chamber to the exterior of the body, a valve normally closing the outlet, and means functioning with the upward movement of the body a predetermined distance from said lowered position to open the valve.

3. A jar comprising a body adapted at its lower end for connection to a spear or like tool, a spindle slidable in and projecting from the upper end of the body for connection to a suspending means, means between the spindle and body positively limiting the upward movement of the spindle from a predetermined lowered position in the body, an expansible member mounted on the spindle within the body adapted when expanded to frictionally grip the inner wall of the body, hydraulic pressure means to thus expand said member, a liquid chamber in the body in free communication with the interior of the member whereby said chamber will fill with the liquid supplied to the member, an outlet from said chamber to the exterior of the body, said outlet being below said member and its inner end facing upwardly, a valve element movably seated on said end of the outlet, and means supported by and depending from the spindle to engage and lift said element from its seat with the upward movement of the spindle a predetermined distance from said lowered position.

4. A jar comprising a body adapted at its lower end for connection to a spear or like tool, a spindle slidable and projecting from the upper end of the body for connection to a suspending means, means between the spindle and body positively limiting the upward movement of the spindle from a predetermined lowered position in the body, an expansible member mounted on the spindle within the body adapted when expanded to frictionally grip the inner wall of the body, hydraulic pressure means to thus expand said member, a liquid chamber in the body below the member and spindle in free communication with the interior of said member whereby the chamber will fill with the liquid supplied to the member, a vertical outlet pipe centralized in said chamber and providing a passage to the exterior of the body below the chamber, an upwardly movable valve larger than the pipe normally seated on the open upper end of the same, a sleeve mounted on and depending from the spindle about and in spaced relation to the pipe and valve, and elements projecting inwardly from said sleeve below the valve to engage and raise the same off its seat when the sleeve and spindle have been raised a predetermined distance from said lowered position.

5. A jar comprising a body adapted at its lower end for connection to a spear or like tool, a spindle slidable in and projecting from the upper end of the body for connection to a suspending means, 5 said spindle having an axial passage therethrough adapted at its upper end for connection to a source of hydraulic pressure, means between the spindle and body to positively limit the upward movement of the spindle from a predetermined lowered position in the body, an enclosed chamber in the body about the spindle and with which the lower end of the spindle passage freely communicates, an expansible pressure-tight tube about the spindle and at its ends having pressure

tight connection therewith, the spindle having a side port intermediate the ends of the tube providing communication with the spindle passage, a resilient expansible sleeve about the tube adapted, when said tube is expanded, to frictionally grip the wall of the chamber, means holding said tube and sleeve against movement along the spindle, a liquid outlet from the chamber, means normally closing the outlet, and means functioning with the upward movement of the spindle from its lowered position to open said outlet closing means. 10
